RULE FOR CUTTING ROOF RAFTERS.

APPLICATION FILED JUNE 14, 1919.

Patented June 15, 1920.

2 SHEETS—SHEET 2.

UNITED STATES PATENT OFFICE.

WARNER A. WINN, OF CLARKSVILLE, TENNESSEE.

RULE FOR CUTTING ROOF-RAFTERS.

1,343,604.

Specification of Letters Patent. Patented June 15, 1920.

Application filed June 14, 1919. Serial No. 304,175.

To all whom it may concern:

Be it known that I, WARNER A. WINN, a citizen of the United States, residing at Clarksville, in the county of Montgomery and State of Tennessee, have invented certain new and useful Improvements in Rules for Cutting Roof-Rafters, of which the following is a specification, reference being had to the accompanying drawings.

10 This invention relates to rules, and particularly to instruments of this class designed for the purpose of marking the cuts to be used on the rafters of roof frames.

In the construction of ordinary roofs 15 there are common rafters, jack rafters, hip and valley rafters, and cripple rafters, and these rafters have to be cut so as to fit at the base against the plate and against the ridge. Each rafter, therefore, has to be formed with 20 a top cut and a bottom cut or heel cut. Certain of the rafters, as for instance, the jack, hip, valley and cripple rafters, in addition to being angularly cut at their ends, must be beveled properly so as to fit against the 25 ridge rafter and against the other rafters with which they are used.

Heretofore, these cuts have been usually marked by means of steel squares or like instruments which are formed on their two 30 arms with a plurality of rows of graduations, a different row of graduations being used for each cut to be made, and considerable calculation is necessary in order to use these steel squares and make the proper cuts. 35 Not only this, but it is an easy matter for a person using the steel square to make a mistake unless great care is used. Steel squares can only be used by those expert in their use.

The general object of my invention is to 40 provide an instrument which may be adjusted without difficulty in accordance with a very simple series of graduations and which, when adjusted, will provide for marking the top and bottom cuts of common rafters, the top and bottom cuts of jack rafters, and the bevel for the face thereof where the jack rafter is joined to the hip rafters. And it may also be used for marking 45 the proper angle of the top cut and the proper double bevel for hip and valley rafters, and for cripple rafters without readjustment, the instrument being so constructed that when it is set it may be used 50 without readjustment for all of the rafters of a plain roof.

A further object is to provide a construction of this kind which may be easily adjusted for roofs of any desired pitch.

And another object is to provide an instrument of this kind which may be also 60 adjusted for roofs where the pitch of one side of the roof is different from the pitch on the other side of the roof.

Still another object is to provide a device of this character wherein one of the rules 65 may be angularly adjusted to any desired relation to the main frame of the rule so as to mark off any desired angle on a board or plank.

Other objects will appear in the course of 70 the following description.

My invention is illustrated in the accompanying drawings, wherein:—

Figure 1 is a face view of an instrument constructed in accordance with my invention; 75

Fig. 2 is a side elevation thereof:

Fig. 3 is a section on the line 3—3 of Fig. 1;

Fig. 4 is a section through one leg of the 80 pivoted square, showing the manner of attaching the arc thereof;

Fig. 5 is a sectional view through the arc showing the means for clamping it in adjusted positions; 85

Fig. 6 is a section on the line 6—6 of Fig. 5;

Fig. 7 is a side elevation of the instrument applied to marking an end cut for a rafter; and 90

Fig. 8 is a face view of the instrument shown in Fig. 7 showing the manner in which the bevel for a jack rafter is marked.

Referring particularly to Figs. 1 and 2, it will be seen that my instrument comprises a 95 rectangular frame. I do not wish to be limited to the particular construction of this frame, but as illustrated, it comprises two transversely extending end bars 10 and two pairs of longitudinally extending strips or 100 bars 11, each of which is angular in form to provide a flange 12. The flanges 12 extend in opposite directions. These angular strips 11 are spaced from each other by the transverse strips or bars 10 which are disposed between the angular strips. These strips 11 and 12 at the corners of the frame are held together by means of wing nuts and bolts 13.

Movable longitudinally of the main frame 110

is a sliding frame formed by a pair of parallel cross bars 14 and 15, rigidly connected by longitudinal strips 16, which strips 16 are folded longitudinally so as to embrace one of the strips or bars 11, as illustrated in Fig. 3. These frame members 16 are longitudinally slotted, as at 17, (see Fig. 1) for the passage of bolts 18 carrying clamping wing nuts. By loosening the nuts and bolts 18, the frame formed of the members 14, 15 and 16 may be longitudinally shifted along the main frame and then adjusted and held in their adjusted positions.

Pivotedly mounted upon the cross bar 14 is a "square", that is a right angular member composed of two legs 19 and 20, the leg 19 being preferably longer than the leg 20. The leg 20 is provided at its upper end with an aperture for the passage of the cross bar 14, which is round in cross section, and suitable means, as for instance collars 14^a, are provided for holding this "square" in a middle position on the cross bar 14. The legs 19 and 20 are hinged to each other by a hinge 21 so that they may be folded into parallel relation, but in use these legs 19 and 20 are always disposed in right angular relation and held therein by an arcuate bar 22. This bar at its ends is angularly bent, as at 23, and as illustrated in Fig. 4, this angularly bent foot 23 is held clamped against the inner faces of the arms by means of a bolt 24 and wing nut 25. The foot 23 is also provided with a pin 26 which enters a perforation in the face of the member 19 or 20 so as to hold this arcuate cross bar 22 in the same plane with the two legs 19 and 20. It will be seen from Fig. 3 that the legs 19 and 20 have lateral flanges 27, and from Fig. 4 that the nuts 25 are entirely disposed within the channels formed by these flanges. The arcuate cross bar 22, as shown in Fig. 3, is longitudinally slotted, as at 28, and for the purpose of adjusting the "square" and holding it in its adjusted position, I provide clamping means on the arc 22 which engages the arc with the cross bar 15.

As illustrated in Fig. 5, I provide a washer 29 having a head which is rectangular in cross section and fits within the slot 28, and passing through this washer is an eye-bolt 30 having an eye, as illustrated in Fig. 6, through which the transverse rod 15 passes, and this bolt carrying a nut 31. The washer 29, as shown in Fig. 6, has an opening for the passage of the bolt, this opening being flared toward the rod 15. By this means it is obvious that the arc 22 may be shifted relative to the bolt 30 and then clamped tightly in its adjusted position and held from any accidental movement.

Coacting with each of the corner bolts 13 at that end of the main frame adjacent the cross rod 14, is a pair of blades constituting rules, designated 32. Each of these blades

is longitudinally slotted, as at 33, for the passage of bolt 13, and when the wing nut on this bolt is clamped down, it will be obvious that the corresponding rule 32 will be held from movement. It will also be seen that these rules or blades may be shifted longitudinally or rotated with respect to the bolt upon which they are mounted. Preferably, one or both of the blades is slidably mounted upon a rectangular block 34, through which the bolt 13 passes, this block being rotatable upon the bolt and the rule being shiftable along this block. Preferably also, this block carries upon it a circular dial 35 having graduations upon its perimeter, coacting with an index mark 36 on the frame. This dial is graduated in degrees, and by this means the angle of the corresponding blade with the longitudinal axis of the main frame will be indicated. The inner ends of the blades 32 are beveled, as at 37, and the pointed ends of these blades are adapted to be disposed against the extreme edges or corners of the channel-shaped leg 20, as shown most clearly in Fig. 1.

In the use of this device, it will be obvious that the sliding frame formed of the parts 14, 15 and 16 and carrying the square formed of the legs 19 and 20 and the arc 22, may be longitudinally shifted upon the main frame, and that if the square-carrying frame is shifted away from that end of the main frame upon which the blades 32 are mounted, the blades have to be shifted to a more acute angle in order to engage with the legs 22 than if the square supporting frame is shifted toward that end of the main frame supporting these rules or blades 32. It will likewise be seen that the legs 19 and 20 are always disposed at right angles to each other, but that they may be shifted into varying relations with the plane of the main frame by turning this square, composed of the legs 19 and 20, upon the pivot formed by the cross rod 14.

As illustrated in Fig. 3, the arc has on one longitudinal edge a scale A having thereon subdivisions indicating inch rise to foot run. This scale A is for the purpose of adjusting the "square" to indicate the top and bottom cuts of common rafters, jack rafters and cripple rafters. On the opposite edge of the arc there is disposed a scale C which is also marked off by subdivisions indicating inch rise to foot run, and this scale C is to be used for marking the bottom and top cuts for hip and valley rafters. On the face of the main frame, as illustrated in Fig. 1, there is disposed a scale B having subdivisions from 2 to 24 indicating inch rise to foot run, this scale being for the purpose of adjusting the sliding frame in the main frame so as to give the proper angles to the rule blades 32 to indicate the bevels

on the side faces of the jack rafters and cripple rafters. On the opposite edge of the main frame from scale B and preferably on the same face as said scale, there is a scale 5 D for the adjustment of the sliding frame within the main frame, to thereby indicate the proper adjustment of the rule blades 32 in order to secure the proper bevels for the hip and valley rafters. Disposed beyond 10 the scale B and preferably on the same face, though not necessarily so, and coacting with the lower cross rod 15, is a scale E, also marked in subdivisions indicating inch rise to foot run, used for marking jack and 15 cripple rafters where one side of the roof has a different pitch from the other side of the roof. On the opposite edge of the main frame there is another scale F which is to be used for the hip and valley rafters 20 where the two sides of the roof have different pitches.

When a common rafter is to be cut, the square formed of the members 19 and 20, is rotatably adjusted upon its pivot 14, by 25 reference to scale A, on the arc 22 until one limb, as for instance, the limb 19 is disposed at the proper angle for the top cut. The other limb 20 will then be disposed in proper position to indicate the bottom cut, 30 as will be obvious. The main frame is then disposed against the edge face of the rafter, as indicated in Fig. 7, with the limb 19 disposed against the side face of the rafter and the top cut is then marked. The 35 frame is then reversed so that the leg 20 lies across the face of the rafter and the frame is shifted down the rafter a proper distance and the bottom cut marked. The bottom and top cuts will always be at right 40 angles to each other.

The same operation is performed in marking jack rafters, except that in this case the sliding frame, formed of the members 14, 15 and 16, and carrying the square, is adjusted along the main frame in accordance 45 with scale B, the end b of one of the members 16 being the index mark coacting with the scale. When the sliding frame has been adjusted, one or both of the blades 32 is adjusted in the manner illustrated in Fig. 1, 50 and then after the top cut has been marked, the main frame is turned at right angles to the side face of the rafter and then one of the rule blades 32 will extend diagonally across the edge of the rafter, as indicated 55 in Fig. 8, and this marks the bevel edge given to the jack rafter. Of course, for half of the jack rafters, the rule blade indicated in Fig. 8 will be used. For the 60 other half, that is for those on the other side of the hip rafter, the other blade will be used, giving a reverse angle. Of course, what is true in marking jack rafters is also true with regard to marking cripple rafters. 65 In marking hip or valley rafters, the

sliding frame is set in the main frame with relation to the hip and valley scale D, while the square is set with relation to the hip and valley scale C in Fig. 3. One limb of the square will give the top cut and the other 70 limb the bottom cut. The frame is then turned in the manner indicated in Fig. 8 so as to carry one of the rules across the edge of the rafter and a diagonal line is drawn, and then the frame is shifted so that the 75 square is disposed against the opposite face of the rafter and the other rule blade 32 is used to draw a second diagonal line intersecting the first diagonal line on the edge 80 face of the rafter and the limb of the square is used to draw a second end cut line, which will, of course, be directly opposite the first end cut line. These lines will then indicate the cuts to be made in order to form the hip rafter with a double bevel end which will 85 fit the ridge rafter and the common rafters intersecting the ridge rafter at the end thereof. What is true of the hip rafters is also true of the valley rafters, except that these are formed at their ends with V- 90 shaped notches instead of with V-shaped forwardly convergent, beveled faces.

Where the roof has one side of one pitch and the other side of a different pitch, then the scales E and F for the jack rafters and 95 the hip and valley rafters will be used in an obvious manner.

It will be seen that my device is extremely convenient, that it does away with all necessity of calculating or with the necessity 100 of a skilled knowledge of the use and manipulation of the "steel square" or framing square, and requires only that the operator shall adjust the device according to the scales, which may be readily done. It is obvious also that the device may be folded so that it will lie all in the same plane for carriage, and it is obvious also that the frames might be formed in sections so as to be readily taken apart. 110

While I have illustrated a form of my invention which I have found to be extremely practical and effective, I do not wish to be limited to the details of the construction illustrated; as these might be modified in 115 many ways without departing from the spirit of the invention.

I claim:—

1. An instrument of the character described, comprising a relatively flat base 120 adapted to be applied against the edge face of a rafter, a square having two limbs at right angles pivotally mounted upon the base at the intersection of the limbs for movement in a plane at right angles to the 125 plane of the base, and means for holding the limbs in rectangular relation and holding the square with a limb at any desired angle with relation to the plane of the base.

2. An instrument of the character de- 130

scribed comprising a rectangular frame having side members and end members and adapted to be disposed against the edge face of a rafter, a square having two legs disposed at an angle to each other and pivotally mounted in said frame, the pivotal axis of the legs being disposed in the plane of the frame and extending through the square at the intersection of the legs, an 10 arcuate member connecting said legs, and a cross bar on the frame over which said arcuate member passes and having means whereby the arcuate member may be clamped and the square held at any desired 15 angular relation to the main frame.

3. An instrument of the character described comprising a rectangular frame having side members and end members and adapted to be disposed against the edge face 20 of a rafter, a square having two legs disposed at an angle to each other, and pivotally mounted in said frame, the pivotal axis of the legs being disposed in the plane of the frame and extending through the 25 square at the intersection of the legs, an arcuate member connecting the legs and longitudinally slotted, a transverse member mounted on the frame and having a clamping bolt passing through said slot, 30 and a clamping nut engaging the bolt, the arcuate member at one side of the slot being provided with a scale by which the arcuate member may be adjusted.

4. An instrument of the character described comprising a rectangular frame 35 having end members and side members and adapted to be applied against the edge face of a rafter, a cross rod carried by said frame, a square having two limbs at right 40 angles pivotally mounted at the intersection of the limbs upon said rod, an arcuate member connecting said legs and holding them at right angles, a cross bar on the frame, a clamping bolt and nut on the cross bar operatively 45 engaging said arcuate member to hold the square in any adjusted position, the arcuate member having a scale indicating inch rise to foot run of a roof whereby 50 said square may be set with reference to the plane of the frame to indicate the top and bottom cuts of rafters.

5. An instrument of the character described comprising a rectangular frame adapted to be applied against the edge face 55 of a rafter, a square having two limbs disposed at right angles to each other, the square being adjustable upon and longitudinally with relation to the main frame and being pivoted to swing into angular 60 relation to the plane of the main frame, and a rule blade pivotally and slidably mounted at one corner of the frame adjacent the intersection of the limbs of the square and being thereby adjustable lengthwise of itself 65 and angularly adjustable with relation to

the main frame and in a plane parallel thereto to bring one corner in coincidence with the apex of the square at the pivotal point thereof.

6. An instrument of the character described comprising a rectangular frame having end members and side members and adapted to be applied against the edge face of a rafter, a square having two legs at right angles to each other and disposed 70 within said frame, a sliding frame slidably mounted upon the main frame and including two cross rods, one of said rods passing through the square at the intersection of its limbs and forming a pivot for the 75 square, an arcuate member connecting the limbs of the square, a clamping member on the second named rod engaging said arcuate member, the arcuate member being formed with a scale indicating inch rise to foot 80 run of a roof rafter, one side of the frame being formed with a scale by which the sliding frame is longitudinally adjusted upon the main frame and indicating inch rise to foot run, and a rule blade pivotally 85 and slidably mounted at one corner of the frame adjacent the rod upon which the square is pivotally supported, said rule blade being thereby adjustable longitudinally of itself and angularly with relation 90 to the main frame to bring one corner in coincidence with the apex of the square at the pivotal point thereof.

7. An instrument of the character described comprising a rectangular frame 100 having end members and side members and adapted to be applied against the edge face of a rafter, a square having two legs at right angles to each other and disposed within said frame, a sliding frame slidably mounted upon the main frame and including two cross rods, one of said rods passing through the square at the intersection of its limbs and forming a pivot for the square, an 105 arcuate member connecting the limbs of the square, a clamping member on the second named rod engaging said arcuate member, the arcuate member being formed with a scale indicating inch rise to foot run of a roof rafter, one side of the frame being 110 formed with a scale by which the sliding frame is longitudinally adjusted upon the main frame and indicating inch rise to foot run, and rule blades pivotally and slidably 115 mounted at the corners of the frame adjacent the pivotal center of the square, said rule blades being disposed normally in a convergent relation and each being adjustable longitudinally of itself and angularly 120 with relation to the main frame to bring their extremities in coincidence with the apex of the square at the pivotal point thereof.

8. An instrument of the character described comprising a rectangular frame hav- 125

ing side members and end members, a sliding frame slidably mounted upon the main frame and including two cross rods, a square having two limbs at right angles to each other and pivoted at the intersection of the limbs upon one of said rods, an arcuate member attached to the limbs of the square and coacting with the other of said rods, a clamp upon said last named rod adapted to engage said arcuate member to hold the square adjusted in any desired position, rule blades pivotally and slidably mounted at the corners of the main frame adjacent the pivotal axis of the square whereby the rule blades may be longitudinally and angularly adjusted to bring their extremities in coincidence with the apex of the square at the pivotal point thereof, and means for holding the sliding frame adjusted in the main frame and the rule blades adjusted with relation to the sliding frame and main frame, the arcuate member being provided on its face with a common rafter scale and a hip and valley scale whereby the square may be angularly adjusted with reference to the plane of the main frame, said members of the main frame being provided with a jack and cripple rafter bevel scale and with a hip and valley bevel scale whereby the sliding frame may be adjusted.

9. An instrument of the character described comprising a rectangular main frame formed of two pairs of side members, each side member being angular in form, transverse members detachably connected to the side members and having their ends disposed between each pair of side members, a sliding frame comprising side members sliding between the side members of the main frame and longitudinally slotted, cross rods connecting said side members of the sliding frame, clamping bolts passing through the side members of the main frame and through the slots of the side members of the sliding frame, a square having two limbs hinged to each other, a longitudinally slotted, arcuate member normally attached to said limbs and holding the limbs in rectangular relation, one of said cross rods

passing through the square at the intersection of said limbs and the other cross rod coacting with the arcuate member, the bolt on said last named cross rod extending through the slot of the arcuate member, a clamping nut on the bolt, and longitudinally slidably, pivotally mounted rule blades disposed at the corners of the main frame adjacent the apex of the square and having their inner ends beveled to form points, said rule blades being adjustable to bring their points into coincidence with the apex of the square at the pivotal point thereof, the arcuate member being provided with a common rafter pitch scale, and a hip and valley pitch scale, and the main frame being provided with a jack and cripple rafter bevel scale and a hip and valley bevel scale with relation to which the sliding frame is adjusted.

10. An instrument of the character described comprising a relatively flat base adapted to be applied against the edge face of a rafter, and a marking instrument having two limbs disposed in divergent relation to each other and being pivotally mounted at the intersection of its limbs upon the base for bodily movement in a plane at right angles to the plane of the base, said limbs being connected by an arcuate member having graduations whereby the angular adjustment of the instrument relative to the base may be determined.

11. An instrument of the character described comprising a flat base adapted to be applied against the edge face of a rafter, a sliding frame mounted upon the base for sliding movement on the base in the plane thereof, and a marking blade swingingly mounted upon said sliding member for movement in a plane at right angles to the plane of the base and sliding member and for adjustment into different angular relations to the plane of the base.

In testimony whereof I hereunto affix my signature in the presence of two witnesses.
